HEAT EXCHANGE UNIT

James W. McGuffey, Lansing, Mich., assignor to Tranter
Manufacturing, Inc., Lansing, Mich., a corporation of
Michigan

Filed Oct. 23, 1967, Ser. No. 9,123

Term of patent 14 years

U.S. Cl. D23—72
Int. Cl. D23—03

FIG.2

FIG.1

FIG.3

FIGURE 1 is a perspective view of a heat exchange unit showing the new design.

FIG. 2 is a front elevational view thereof.

FIG. 3 is an enlarged scale fragmentary cross-sectional view taken on line 3—3 of FIG. 2.

FIG. 4 is a top plan view of the heat exchange unit.

FIG. 5 is a right end elevational view thereof.

FIG. 6 is a rear elevational view thereof.

FIG. 7 is a left end elevational view thereof.

I claim:

The ornamental design for a heat exchange unit, substantially as shown and described.
